OF OLINDA, CALIFORNIA.

PROCESS OF PURIFYING OIL.

1,004,210.

Specification of Letters Patent. Patented Sept. 26, 1911.

Application filed January 20, 1910. Serial No. 539,196.

To all whom it may concern:

Be it known that I, WILLIAM J. TRAVERS, a citizen of the United States, residing at Olinda, in the county of Orange and State of California, have invented a new and useful Process of Purifying Oil, of which the following is a specification.

In crude oil found in certain localities, as in some sections of California and Mexico, water is contained in the oil to such an extent, as to render the oil unacceptable to transportation and consuming companies, and the separation of the water from the oil by the process of heating and settling is not practicable, the water being so emulsified or mixed with the oil that it does not settle out, even on heating. The present practice in these localities, when the quantity of water is not too great, is to heat such oil in tanks, 20 by means of steam coils, so as to drive off or evaporate the water. In some cases the amount of water contained is so great that this operation is not commercially practicable, and the oil is destroyed by burning or is 25 allowed to accumulate in sumps, constituting a nuisance. Such oils being of an asphaltic base are tenacious in nature and the water found in emulsion with such oils has the general appearance of being entangled 30 or enveloped in a tenacious asphaltic film which is of sufficient strength to inclose and retain such moisture even after such oil and water has been heated to a temperature of 212° F., if it is subject to the hydrostatic 35 pressure of its own body, and I have discovered that such asphaltic film is not of sufficient strength or tenacity to retain the water if the same is heated to 212° F. or the boiling point of water and the hydrostatic 40 pressure of the oil is removed and I have also discovered that by bringing an emulsion of oil and water of the character described, up to a temperature sufficient to vaporize such water and then reducing the 45 hydrostatic pressure upon the entangled water by lessening the depth of immersion of such entangled water to a minimum, that such water will break from the oil film and pass off from the body in vapor form.

50 When heat is applied to the oil by means of coils through which steam or other heating agent has been circulated, such operation does not uniformly heat the oil, as the unequal heating of different parts of the

body of the oil by the coils, causes a continual circulation with resulting commingling of the oil with the water.

My invention consists essentially in heating the oil to or above the boiling point of water at atmospheric pressure, and then 60 slowly admitting the oil to the bottom of a heated mass of oil at said temperature, causing the heated oil to rise gradually and uniformly, and to be exposed to the atmosphere at the top of said body, whereby the steam is 65 allowed to evaporate or escape from the surface of the oil as it reaches the top of the body of the oil in the tank.

As the oil rises, its hydrostatic pressure decreases, and is entirely removed when the 70 oil reaches the top, enabling the water vapor to break through the envelop or film of asphaltum entangling the same, and to escape from the body of the oil.

The accompanying drawing illustrates one 75 form of apparatus for carrying out the process, the figure being a diagrammatic view.

1 designates the separating tank having its top open to the atmosphere as shown. 80 The oil is introduced into the bottom of the tank 1 through a pipe 2 which leads from a receptacle 3. Heat is applied to the oil and water while it is within the receptacle 3 by the means of the fire 4.

5 is an overflow pipe leading from the tank 1.

The oil is delivered to the receptacle 3 through a pipe 6 and may be pumped there-through by a pump 7.

8 designates a tank for holding the oil to be treated.

9 designates a tank for receiving the oil after it has been treated.

The oil to which my process is applied is 95 California crude oil or the like, having an asphaltic base, with a gravity of 14° to 30° Baumé, and containing from 5 to 50% or more of water entangled or emulsified with the oil and asphaltum forming the substance 100 known as B. S.

The oil is pumped to the receptacle 3, which is preferably closed and is heated therein, preferably to a temperature of somewhat above 212° F., and passes through 105 the pipe 2 into the bottom of the open tank 1. It is desirable to heat the oil sufficiently above 212° F. to provide for the heat lost in

passage through the apparatus so that the oil will be at substantially the boiling point of water when it reaches the top of the open tank. On account of the large body of oil used the heat lost by radiation, etc., is comparatively small so that the temperature of heating in the receptacle 3 need be but slightly above 212° F. The hot oil which continually enters the open tank 1 keeps the body of oil within the tank, at a substantially uniform temperature throughout. The upward movement in tank 1 is very slow, the oil being supplied to the tank, for example, at such rate that ten hours or more are required for replenishing the contents of the tank. The area of the surface of oil which is exposed to the atmosphere in the tank 1 is considerable, so that the vapor which rises from the top of the oil is readily assimilated by the air.

The condition of the oil being treated may be determined from time to time by testing it in a centrifugal testing device, or

by observing the character of the foam on top of the body of oil.

What I claim is:

The method of removing water from oil having an asphaltic base and in which the water is so contained that it does not settle out in heating, which consists in heating the oil to or above 212° F. introducing the heated oil slowly into the bottom of a heated mass of oil at substantially the same temperature, causing the oil to gradually and uniformly rise to the surface of said mass, so as to gradually reduce and remove the hydrostatic pressure in the oil, and allowing the water to evaporate, and escape from the oil as it reaches the surface.

In testimony whereof, I have hereunto set my hand at Los Angeles, California, this 15th day of January, 1910.

WILLIAM J. TRAVERS.
